OVERHEAD DOOR FOR FILLING STATIONS
AND THE LIKE

Orie L. Meek, Clarksburg, W. Va.

Application August 15, 1950, Serial No. 179,620

5 Claims. (Cl. 268—58)

1

This invention relates to a door of the type which is normally closed in a vertical position and may be opened by movement into a horizontal plane. This type of door which is provided with trackways for guiding the same from the vertical to a horizontal position is more commonly known as an overhead door and is used, for example, in garages, warehouses, and various other type buildings. In particular, this invention is concerned with an arrangement operated by fluid means for opening a door of the type described.

An important object of this invention is to provide such a door which may be operated with fluid means and requires a minimum of space overhead between the horizontal trackway and the ceiling of the building for containing the operating mechanism.

Another important object of this invention is to provide the aforesaid operating means with a new and novel booster bar type mechanism which stores potential energy upon the opening of the door capable of closing the door upon the release of the fluid pressure in the fluid means.

A further additional object of this invention is to provide a simple and effective mechanically operated catch means for retaining the door in its open position and for preventing the operation of the booster bar upon release of fluid pressure if desired.

A still further object of this invention is to provide a door of the type described which may be opened by the movement of a carriage along a horizontal trackway in response to fluid driving means, the length of the movement of the carriage because of the mechanical advantage obtained by the arrangement being only one-half the distance that the door must move in order to be in a fully opened position.

Other important objects and purposes of this invention will become apparent from the following description taken in conjunction with the drawings wherein:

Fig. 1 is a top plan view of the door operating means;

Figure 2 is a side elevational view of Figure 1;

Figure 3 is a cross-sectional view taken along the line 3—3 of Figure 2;

Figure 4 is an enlarged fragmental view of the left end portion of Figure 3; and

Figure 5 is a vertical cross-sectional view taken along the line 5—5 of Figure 4.

With reference to the drawings, there is shown in Figures 1 and 2 an exterior wall 10 of a building such as a garage or the like having a doorway 12 formed in the wall. Adjacent the opposite jambs of the door opening 12 are substantially vertically extending guideways or tracks 14 connected by means of arcuate guideway or track portions 16 to guideways or tracks 18 which extend inwardly in a substantially horizontal plane above the opening 12 and are supported by means fixed to the overhead. This trackway, designated as a whole as 20, in its preferred form comprises

2

two parallel channel members with the legs thereof extending inwardly from the opposite jambs of the opening 12 towards each other.

Supported by and guided in the trackway 20 by means of anti-friction rollers 22 is a door indicated as a whole at 24 which, as shown, may consist of a plurality of horizontal sections 26 hinged together. This door is of a length sufficient to close the opening 12. From the above description it is apparent that the door may be opened in the usual manner by lifting it upwardly and permitting the door to be guided into the horizontal plane defined by the trackway 18.

An additional trackway 28 consisting preferably of guide members 30 in parallel relationship with one another and located in a horizontal plane above the top of the opening 12 is provided for guiding and carrying a fluid driven carriage member 32 described hereinafter. In the preferred form as shown in Figures 3 and 4, trackway 28 consists of two angle members 30, one of

which is fixed by means of a leg 34 to the outer side of web 36 of one of the channels 18, the other leg 38 of this member 30 extending outwardly thereof in the plane of the lower leg 40 of the channel member 18'. The other carriage supporting and guiding angle member 30 is positioned in an identical manner by affixing it to the other channel member 18 of the trackway 20.

As shown in the drawings, in the preferred form, trackway 28 is about one-half the length of the trackway 18 which latter track is of a length at least equal to the length of the door. Furthermore, trackway 28 is affixed to the rearward half of trackway 18. Reasons for this positioning will become apparent from the description given hereinafter.

Fluid operated carriage 32 which is carried and guided by trackway 28 comprises in its preferred form a transversely extending body member 42, preferably of an angle iron as shown, and supporting means 44 at each end thereof. Members 44 are each provided with a pair of roller bearing type wheels 46 and the distance between members 44 and the parallel relationship of the direction of travel of wheels 46 of each member 44 may be adjusted by means of slots 58 which are provided in each end of the body member 42 and receive members 44. This adjustable feature permits adjustment of the carriage 32 relative to the trackway 28 in order that the former may move along the track properly without any objectionable binding or wedging.

Fluid driving means, indicated as a whole at 48, are provided for moving carriage 32 along the trackway 28. As shown, the fluid means 48 comprises a cylinder 50 which is fixed at one end to the wall 10 at a position above the opening 12 and preferably substantially at the midpoint of the same, the longitudinal axis of cylinder 50 being in a horizontal plane. Within the cylinder 50 is a piston, not shown, operating a connecting rod assembly 52, the free end 54 of the connect-

ing rod 52 being attached to preferably the mid-point of the member 42 by means such as the flange and bolt arrangement 56 as shown. As described hereinafter, movement of the piston and connecting rod 52 to the right will move the carriage 32 in the same direction along the trackway 28.

For the purpose of operably connecting the carriage 32 to the door 24 in order that it may be opened upon application of fluid pressure to the cylinder 50, a pulley 60 is provided towards each end of the body member 42 of the carriage 32. An additional pulley 62, preferably in the same horizontal plane as the pulley 60, is fixed to the frame 10 at a position vertically above each of the guides or rails of the trackway 14. On each side of the trackway 20 there is a wire cable 64 fixed at one end at a position such as 66 between the frame 10 and the forward end of track 28. Cable 64 is received over the pulley 60 and its companion pulley 62, and is then connected at its other end 68 to the base of the door 24. The arrangement of pulleys 60 and 62 and the wire cables 64 as described provides a two to one mechanical advantage whereby it is seen that upon operation of the fluid cylinder 50 moving the carriage 32 to the right and away from the frame 10 along the trackway 28, the door 24 is opened. The door 24 travels during its opening twice the distance of the carriage 32 and therefore, as previously pointed out, the length of the trackway 28 need be only one-half of the length of the trackway 14. In the door's fully opened position, as shown in phantom in Figure 2, the upper edge of the door is in a position adjacent the carriage 32.

A booster bar 70 notched at each of its ends at 72 and slidably received thereby by the upper channel legs 14 transversely across track 18 is provided for engagement with the door 24 as it is moved along the trackway 20 towards its open position. At each end of the booster bar 70 there is a spring 76 whose other end is attached to a fixed point such as 78. Stops 79 are provided as shown for preventing the movement of the booster bar 70 towards the doorway 12 beyond that point at which the springs 76 are just in tension. Upon opening door 24 and contact of the upper edge thereof with booster bar 70 and movement of bar 70 to the right, as shown in Figure 2, springs 76 are tensioned and store potential energy for returning the door to a closed position upon release of fluid pressure in cylinder 50. It is to be understood that the booster bar 70 although shown in its preferred form as being guided on trackway 20 by notches 72, may be supported by an additional trackway or other means in the same plane as the horizontal plane in which the door moves upon opening if desired.

A spring operated catch 80 pivoted at a point such as 82 is provided for locking the carriage member 32 in the position it occupies upon the complete opening of the door 24. This catch, the end of which cooperates with the vertical leg of the angle member 42 prevents the action of the booster bar 70 from closing the door even upon release of the fluid pressure in cylinder 50. A cable 84 is provided for operating the catch 80 against the spring action 86 which normally retains the catch in a locking position. This cable may lead to any desired station for convenient operation.

For the purpose of returning the carriage 32 to the position on the inner end of track 28

occupied when the door is closed, a spring 88 is provided at each end of the body member 42 of the carriage 32, the other end being fixed to the frame member 10 in the position shown. These springs 88 are tensioned upon movement of the carriage 32 to the right in opening the door 24 and provide thereby the energy required to return carriage 32 to the inner end of track 28 upon release of catch 80.

The control for operating the fluid cylinder and piston 48 may be located at any convenient position either within or outside of the building. As shown diagrammatically it preferably consists of a two-way valve 90, one connection 92 of this valve providing the supply of fluid under pressure and the other line 92 leading to exhaust. The fluid line 94 serves for supplying or exhausting fluid to and from cylinder 50 by way of valve 90.

When it is desired to open the door 24 fluid pressure is admitted through the line 90 to the cylinder 50 and the carriage 32 is moved to the right. By means of the mechanical advantage gained through the pulleys 60 and 62 and the cables 64, movement of the carriage 32 to the right guides the door 24 from its vertical position to a horizontal position along the trackway 20. At the end of the stroke of the piston 52, the door 24 is in its fully opened position and the carriage 32 is prevented from returning to its position occupied upon closing of the door even upon release of the fluid pressure by means of the catch 80. Further, the door 24 upon opening has stored sufficient potential energy in the booster bar 70 for returning the door to its closed position upon release of the catch 80. When closing the door it is readily seen that the carriage 32 is aided in returning to its initial position by means of the springs 88. In addition, the door is prevented from making an appreciable noise upon contact with the threshold since the slack occasioned in cables 64 will just permit closing of the door upon action of the booster bar 70 and the springs 88.

From the above description, it is apparent that an overhead type door has been provided which is operated with fluid means requiring a minimum of vertical space overhead between the horizontal trackway and the ceiling of the building for containing the operating mechanism, that an effective booster mechanism has been provided for closing the door upon release of the fluid pressure and an additional safety catch, and that further the mechanical advantage obtained by the positioning of the overhead door trackway relative to the carriage trackway permits the utilization of a minimum space overhead extending rearwardly from the frame of the building in which the door opening is provided.

As shown in the drawings, pulleys 60 are not located at the extremities of member 42 but are spaced somewhat inwardly thereof. This has been done for the purpose of clarifying the understanding of the drawings. However, in actual practice pulleys 60 are located at the extremities of member 42 in order that no binding action may occur on movement of the cable 64 thereover. Also for the same reason, the ends of spring 76 fixed to the booster bar 70 are spaced somewhat inwardly from the extremities of the same. In actual practice, these springs are at the ends of booster bar 70 in order that they may not interrupt the movement of the door 24 as it progresses against the booster bar 70.

The description of the preferred form of the

invention as set forth is for the purpose of illustration and is not limiting to the scope of the invention as set forth in the claims wherein I claim:

1. A closure structure comprising a door to be raised from a vertical closed to a horizontal open position and lowered therefrom, a trackway to guide said door, said trackway including a pair of spaced guide rails each having vertical and horizontal portions, a second trackway mounted in substantially the same horizontal plane as the horizontal portion of said first trackway, a carriage member movably carried by said second trackway, fluid operating means connected to said carriage member for moving the same along said second trackway, cable means operatively connected between said carriage member and said door for opening said door in response to the movement of said carriage member along said second trackway, resilient means connected between said carriage member and a fixed member for storing energy to return said carriage member to a position normally occupied when said door is closed, and booster means operatively associated with said door when the same is moved through the final portion of its horizontal movement for storing energy to assist in closing of said door, said booster means including a bar mounted in the horizontal path of said door transverse to and slidable along said first trackway for engagement with said door, and spring means connected between said bar and a second fixed member for returning said bar to the position normally occupied when said door is closed and for starting the movement of said door to the closed position.

2. A closure structure of the type in claim 1 wherein a locking member engages said carriage member after said carriage member has traveled the limit of its movement from its normal position to maintain the door in open position.

3. A closure structure comprising a door to be raised from a vertical closed to a horizontal open position, a trackway to guide said door, said trackway including a pair of spaced guide rails each having a vertical and a horizontal portion, means operatively associated with said door for raising the same from the vertical to the horizontal position, and booster means operatively associated with the movement of said door when the same is moved in the horizontal plane for storing energy to assist in closing of said door, said booster means including a bar mounted in the horizontal path of said door transverse to and movable along said trackway for engagement with said door, and spring means connected between said bar and a fixed member for returning said bar to the position normally occupied when said door is closed and for starting the movement of said door to the closed position.

4. A closure structure comprising a door to be raised from a vertical closed position to a horizontal open position, a trackway to guide said door, said trackway including a pair of spaced channel members each having a vertical and horizontal portion, a second trackway mounted in substantially the same horizontal plane as the horizontal portion of said first trackway, said second trackway including angle members rigidly secured to the outer side of the webs of each of said channel members, a carriage member movably carried by said second trackway and including a transverse member to said second trackway, fluid operating means connected to said transverse member for moving the carriage member along said second trackway, cable means con-

nected between fixed points on said channel members, said carriage member and said door, for opening said door in response to movement of said carriage member along said second trackway, at least one spring element connected between said carriage member and a fixed member for storing energy to return said carriage member to a position normally occupied when said door is closed, a locking member engaging 10 said carriage member in its extended position for maintaining the door in the open position, and booster means operatively associated with said door when the same is moved through the final portion of its horizontal movement for storing energy to assist in closing of the door, said booster means including a bar having notched ends for receiving a flange of each of said channel members, said bar being mounted in the horizontal path of said door and transverse to the channel members of said first trackway, and spring means connected to said bar at each end thereof and to fixed points on said trackways for returning said bar to the position it normally occupies when said door is closed and for starting 25 the movement of said door to the closed position.

5. A closure structure comprising a door to be raised from a vertical closed to a horizontal open position, a trackway to guide said door, said trackway including a pair of spaced guide rails each having a flange and a vertical and horizontal portion, means operatively associated with said door for raising the same from the vertical to the horizontal position, a locking member engaging said means when said door is in the open position for maintaining the door in the open position, and booster means operatively associated with the movement of said door when the same is moved in the horizontal plane for 30 storing energy to assist in closing of said door, said booster means including a bar having notched ends for receiving the flanges of said guide rails, said bar being mounted in the horizontal path of movement of said door and transverse to the the guide rails of said trackway, a stop element mounted on each of said guide rails and engaging said bar when the same is in the position normally occupied when said door is closed, and spring means connected to said bar at each end thereof and to fixed points on said 35 trackway for returning said bar to its normal position and starting the movement of said door to the closed position.
